LINE CLAMP

Harry J. D. Wolff, Van Nuys, Calif., assignor to
Ernest A. Huntley, Burbank, Calif.

Application September 9, 1946, Serial No. 695,769

3 Claims. (Cl. 24—134)

1

My invention relates to line clamps, that is, to devices adapted to grip a cable or line to hold the line taut, and included in the objects of my invention are:

First, to provide a line clamp which is particularly suitable for holding clothes lines as well as facilitating tightening the line when needed.

Second, to provide a line clamp which is adapted to hold securely lines of various diameters.

Third, to provide a line clamp wherein the gripping forces are distributed over an appreciable length of the line so as to minimize damage while insuring a firm grip.

Fourth, to provide a line clamp which is particularly simple and economical of construction.

With the above and other objects in view as may appear hereinafter, reference is directed to the accompanying drawings in which:

Figure 1 is an elevational view of one form of my line clamp.

Figure 2 is a similar elevational view of another form of my line clamp.

Figure 3 is an enlarged view of my line clamp with the housing shown in section.

Figure 4 is a sectional view similar to Figure 3 of a modified form of my line clamp as arranged for lines of larger size.

Figure 5 is a sectional view through 5—5 of Figure 3.

Figure 6 is a fragmentary top or plane view of the line clamping cam shown in Figure 3.

Figures 7, 8, 9 are fragmentary transverse sectional views thereof through 7—7, 8—8, 9—9, respectively, of Figure 4.

Figure 10 is a transverse sectional view through 10—10 of Figure 3.

The various forms of line clamps illustrated have features in common which will first be described. My line clamp includes a relatively flat housing 1 defining a cam cavity 2. The cam cavity is open along the lower edge of the housing. At one end there is formed a tubular line guide 3 which is integral with the housing. Curving upwardly from the line guide 3 and forming the upper edge of the housing 1 is a gripping wall 4 which is semicircular in cross section, as shown in Figure 7. Arranged along this wall is a series of gripping ribs 5. The ribs 5 are preferably staggered along opposite sides of a center line disposed approximately 45° to the plane of the housing.

At the end of the housing, remote from the line guide 3 the interior wall thereof curves downwardly from the gripping wall 4 to form a deflecting wall 6. Beyond this wall the housing,

2

except for the arrangement shown in Figure 2, is reduced in width to form a perforated mounting lug or loop portion 7.

With reference particularly directed to Figure 5, the cam cavity 2 receives a cam 8 of oval contour journaled on a pin 9 extending between the sides of the housing 1. The cam 8 is provided with a handle which extends outwardly through the open side of the cam cavity in acute angular relation with the axis of the line guide 3.

The periphery of the cam 8 includes a main gripping section 11 which is concave in cross section and provided with a series of staggered ribs 12. This section of the cam extends from the upper side of the handle 10 to the end of the cam remote therefrom and merges into a secondary gripping portion 13 which is convex in cross section. This portion is interrupted by a series of corrugations 14. Continuing counterclockwise about the periphery of the cam 8 from the secondary gripping portion 13 the cam is again transversely concave to form a guide channel 15.

The proportions of the cam sections and their curvatures are such that the main gripping section 11 is employed when a relatively large line is threaded through the line guide 3, over the cam 8 and down the deflecting wall 6. As will be seen from a comparison of Figures 3, 5 and 6, the gripping wall 4 and main gripping section 11 are complementary and define a line passage equipped with gripping ribs 5 and 12. By reason of the staggered relation of these ribs a line or cable tends to assume a zig-zag contour so that a particularly effective grip is obtained and the gripping force is distributed over an appreciable length, thereby minimizing damage to the line or cable.

If the line clamp is employed to hold lines of relatively small diameter, the secondary gripping portion 13 comes into play. It will be observed by comparison of Figures 5 and 8 that the convex or beveled form of the secondary gripping portion enters into the transversely curved gripping wall 14.

The clamp is brought into operation by rotating the cam handle 10 in a clockwise direction as viewed in Figures 1 and 3 and is released by pressing upwardly or in a counterclockwise direction on the handle.

If the form of clamp as shown in figures except Figure 2 is employed, the mounting lug or loop 7 is suitably anchored by means of a hook and the free end of the line hangs from the housing between the wall 6 and the cam 8. For some uses it is desirable that the line clamp be mounted

intermediate the extremities of a line in which two clamp structures are joined integrally end-to-end as shown in Figure 2, in which case the extra length of line loops downwardly between the two cams. Or if it is desired to join two separate or dissimilar lines the double ended arrangement may be employed.

Reference is now directed particularly to Figures 4, 7, 8 and 9. The construction herein shown is in many respects similar to the arrangement shown in Figure 3. Other than the modification of a transversely corrugated secondary portion 13 the changes are largely those of proportion to render the line clamp particularly suitable for larger sizes.

A cam 21 is mounted on a pin 22 which, it has been found, may best be located slightly higher with respect to the line guide 3. The cam 21 is provided with a peripheral channel 23 occupying the major portion of its periphery except for a handle 24 which extends moveably between the underside of the line guide (which serves as a stop) and a vertical portion.

The initial portion of the channel 23 facing the line guide forms a means for deflecting the line upwardly. Continuing counterclockwise from this portion the cam channel is provided with main gripping portion 25 having ribs 12 similar to those shown in the first described structure. Beyond this portion the sides of the cam are beveled, and the channel 23 is less than a half circle in cross section. This region forms a secondary gripping portion 26 for smaller lines, but in place of the corrugations of the first described structure is provided with gripping ribs 27 similar to but smaller than the ribs 12.

It will be observed from Figure 7 that the sets of ribs 12 and 25 provide a four point engagement of the line and that the beveled sides of the secondary gripping portion shown in Figure 9 enable the cam to enter into the curved gripping wall 4.

Having fully described my invention, it is understood that I do not wish to be limited to the details herein set forth, but my invention is of the full scope of the appended claims.

I claim:

1. A line clamp comprising: a flat housing including a tubular line guide extending from one edge, an edge wall curving laterally from a margin of said line guide, the opposite edge of said housing being open; a cam disk journaled in said

housing and having a handle protruding from the open edge of said housing in angular relation to said line guide; said cam disk including a transversely convex and corrugated portion and a transversely concave portion having a series of transverse ribs, said portions merging one into the other; said edge wall being transversely curved to mate said convex portion and to complement said concave portion.

2. A line clamp comprising: a flat housing including a tubular line guide extending from one edge, an edge wall curving laterally from a margin of said line guide, the opposite edge of said housing being open; a cam disk journaled in said housing and having a handle protruding from the open edge of said housing in angular relation to said line guide; said cam disk including a transversely concave cam section and a transversely convex cam section merging one into the other; the edge wall of said housing being transversely curved to complement said concave cam section and mate said convex cam section.

3. A line clamp comprising: a flat housing including a tubular line guide extending from one edge, an edge wall curving laterally from a margin of said line guide, the opposite edge of said housing being open; a cam disk journaled in said housing and having a handle protruding from the open edge of said housing in angular relation to said line guide; said cam disk including a transversely concave cam section and a transversely convex cam section merging one into the other; the edge wall of said housing being transversely curved to complement said concave cam section and mate said convex cam section; said edge wall and said cam sections having transversely extending rib elements.

HARRY J. D. WOLFF.
